S. 100-115

UNITED STATES PATENT OFFICE

PAUL GANGLER, OF ESSLINGEN, GERMANY, ASSIGNOR TO THE FIRM FR. HESSER,
MASCHINENFABRIK-AKTIENGESELLSCHAFT, OF STUTTGART-CANNSTATT, GERMANY

WRAPPER FEEDING AND GUMMING MACHINE

Application filed March 7, 1928, Serial No. 259,825, and in Germany March 18, 1927.

This invention relates to the machine for wrapping up razor blades forming the object of my prior Patent Number 1,685,601 issued September 25, 1928, and more particularly to modifications of those mechanisms which serve for feeding the wrappers into the machine and applying the adhesive to them, as well as for discharging the wrapped up blades from the machine.

The improved mechanisms are illustrated in the accompanying drawings, by way of example.

Fig. 1 shows a plan of those parts of the razor blade enveloping machine according to my said prior patent application to which the present improvements are essentially applied.

Fig. 2 illustrates in detail the modified mechanism for feeding the wrappers into the machine and applying the adhesive to same, as well as the drive for the modified mechanism for discharging the wrapped up blades from the machine, in elevation,

Fig. 3 is a front elevation of Fig. 2 viewed from the left, the pile of wrappers and the device for raising a wrapper from the pile being omitted for the sake of clearness,

Fig. 4 shows in detail the discharging device in elevation, and

Fig. 5, the same in front-elevation.

The paper wrappers *a* are, as in my prior Patent 1,685,601, piled up in a pile 1 in a frame-like container of the customary and well known kind. Below the front flap of the lowest wrapper, a suitable suction device, for instance a suction nozzle 3 is adapted to oscillate between this flap and a roller 6. The suction pipe of said nozzle 3 is secured in a rotary hollow shaft 4 communicating by a hosepipe 5 with an airpump 7 driven and controlled in the well known manner from the driving shaft 38. The oscillating or rocking motion is imparted to the hollow shaft 4 by an arm 8 suitably mounted upon it, a connecting link 9 and a double-armed lever 10 pivoted upon a bolt 11 and kept in engagement with a suitable cam or eccentric 100, see Fig. 3, of the driving shaft 38, by means of a bowl 13 and spring 14.

The roller 6 is journaled in the pedestals

12 by means of a shaft 15 and is continuously rotated by a spur wheel 16 meshing with the spur wheel 19 keyed to the shaft 18. The shaft 18 is driven by a spur wheel 35 from the spur wheel 102 upon the shaft 27, see Fig. 52, which is continuously rotated by means of a sprocket wheel 28 and a chain 29 from a sprocket wheel 30 keyed to the shaft 38. The chain is kept under tension by a sprocket wheel 31 mounted upon the pin 32 of a rocking arm 33. The roller 6 is provided with an annular groove 6' for the entrance of the suction nozzle 3 and cooperates with a roller 20 which is adapted to be swung from the position shown in dotted lines in Fig. 2 into the operative position shown in full lines, and back again. The roller 20 is adapted to rotate loosely in two double-armed bearing levers 21 which are mounted upon a shaft 22 journaled in the pedestals 12. One of these arms is kept in engagement with the cam 25 keyed to the shaft 18, by means of a friction bowl 23 and tension springs 24 attached to the free ends of the levers 21.

For withdrawing the lowest paper wrapper from the pile, the suction nozzle 3 is in the position shown in full lines and the oscillating roller 20 in the position shown in dotted lines in Fig. 2. After the front flap of the lowest wrapper has been attracted by the suction nozzle 3, this nozzle is swung into the position indicated in dotted lines in Fig. 2, entering the recess 6' in the roller 6, and simultaneously the roller 20 is moved by its described controlling device into the position shown in full lines, whereby the front flap of the paper wrapper is forced by means of said roller 20 against the continuously rotated roller 6 and the wrapper completely drawn off the pile 1 and conveyed to another pair of feed rollers 26 and 34. The roller 26 preferably serves as adhesive applying drum—if desired—and is mounted upon the above mentioned shaft 27 journaled in the pedestals 12. The adhesive applying roller or cylinder 26 is provided with suitably shaped and arranged projections or ribs at those places where adhesive is to be applied to the flaps of the passing wrapper. The wrapper is pressed against the adhesive ap-

plying roller by the other roller 34 continuously rotated by the previously mentioned spur wheel 35 from the spur wheel 102 of the shaft 27 of the adhesive applying cylinder. 5 The adhesive is applied to the adhesive applying cylinder 26 by the roller 36 continuously rotated by a spur wheel 103 from the spur wheel 102 and which picks up the adhesive from the box 37 filled with a suitable adhesive. If it is not desired to apply adhesive to the wrapper, the cylinder 26 and counter drum 34 may be used as simple feeding rollers. 10 After the wrapper has passed the adhesive applying drum 26 and has been provided by said drum with the adhesive at the desired places, it is fed forward on the rotary feed table 105 by means of fingers 138 adapted to oscillate in the direction of the feed. The 15 said fingers 138 form parts of a plate-like piece 139 (Fig. 3) which is secured to an arm 140 rotatably mounted at 141. Oscillation of said arm 140 is effected and controlled by means of a lever 142 which is pivoted on bolt 20 143, connected by link 144 to said arm 140 and held with a bowl 145 in contact with a suitable eccentric 146 keyed upon the driving shaft 38, by means of a tension spring 147 attached to an arm-like projection 142' of lever 25 142. When the wrapper *a* has passed underneath the cylinder 26, the two fingers 138 engage the two lateral flaps of the wrapper from the rear and push it into the position shown in Fig. 2 on to the turntable 105, two 30 angles 170 effecting the lateral guidance of the wrapper. In this position, a holding plate 104 mounted upon a block 39 is lowered on to the wrapper, as described in my prior Patent 1,685,601. The block 39 is guided in 35 a stationary guide member 42 by means of the rods 40, 41 and is under the action of compression springs 43 tending to force the block 39 and thus the holder 104 downwards. For the purpose of controlling this motion, an 40 arm 45 engages a slot in the block 39 by means of a pin 44. This arm 45 is suitably fulcrumed at 46 and kept in engagement with a cam 49 keyed to the shaft 27 by means of a bowl 48 and the said compression springs 43. 45 The discharge of the wrapped up blades is effected by a U-shaped plunger 50 which is guided vertically by means of the rod 51 in a bushing 52 attached to the frame of the machine. The plunger 50 projects with its 50 vertical limbs through openings 53 in the dies 110 of the turntable 105. The plunger 50 has its up and down motion imparted by an arm 55 pivoted by means of the shaft 56 and engaging by means of a sliding block 57 55 the notch of a slotted block 58 mounted upon the rod 51. The arm 55 receives its oscillating motion by a double-armed lever secured to said shaft 56, one arm 150 of said lever being kept with a bowl 153 in contact 60 with a cam keyed on the shaft 18 by means

of a spring 152 attached to the end of the other arm 151 of said lever.

Above the discharging station there is provided a collecting box 58 forming a vertical channel which corresponds in its dimensions substantially with the rectangle formed by the wrapped up blade *k*. At the lower end of this collecting box 58 fingers 60 project slightly into the free channel, said fingers being preferably bevelled inwards below at 75 61 to facilitate the passage of the blades. The fingers 60 are mounted on lateral projections 63 of the box 58 by means of pivots 62 upon which are fixed arms 64 pulled towards each other by a spring 66, so that the fingers 60 80 abut resiliently against the lower edges of the box 58 in the manner shown in Figs. 4 and 5 of the drawings.

When the wrapped up blade is pushed upwards by the ascending plunger 50, it is conveyed from the die 110 into the aperture of the collecting box 58, the blade compressing the fingers 60 outwards to the desired extent, whereupon the fingers 60 fly back behind and below the blade and retain it when the plunger 50 descends again. This arrangement has the advantage that a bursting-open of the blade wrapper flaps is prevented by the piled up blades and the counting and packing of the wrapped up blades is facilitated. 85 90 95

Various changes and modifications may be made in the details of the invention without departing from its spirit, and I desire, therefore, that only such limitations shall be placed thereon as are imposed by the prior art. 100

I claim as my invention:—

In a machine for feeding wrappers from a pile, a suction nozzle arranged beneath said pile and adapted to attract the front end flap of the lowermost wrapper and convey it beyond the pile, a pair of feed rollers one thereof being mounted to swing and press the front end flap of the wrapper against the other feed roller, a second pair of feed rollers into which the wrapper is fed by the first feed rollers, and fingers arranged at the rear of the second feed rollers to feed the wrapper after the latter passes between said second rollers, one roller of the second pair being an adhesive carrying roller to apply adhesive at predetermined places on the wrapper while the latter is being fed between the second pair of rollers. 105 110 115 120

In testimony whereof I have affixed my signature.

PAUL GANGER.
